UNITED STATES PATENT OFFICE.

AUGUSTA PROCTOR, OF VIROQUA, WISCONSIN.

HOLDER FOR LACEWORK.

SPECIFICATION forming part of Letters Patent No. 744,610, dated November 17, 1903

Application filed January 18, 1903. Serial No. 138,879. (No model.)

To all whom it may concern:

Be it known that I, AUGUSTA PROCTOR, a citizen of the United States, residing at Viroqua, in the county of Vernon and State of Wisconsin, have invented certain new and useful Improvements in Holders for Lacework, of which the following is a specification.

This invention relates to the manufacture of lacework by hand, and has special reference to an improved patterning-holder facilitating the preparation and formation of lace-work in various patterns.

To this end the invention contemplates a simple and practical form of device specially designed for the making of the lace popularly known as "Teneriffe" lacework, which is employed as insertion, medallions, and trimming of various styles for shirt-waists, costumes, &c., also being extensively used in the making of fancy linen scarfs, squares, and similar work.

As a general object the invention is specially designed as a distinct improvement upon the form of device disclosed in the patent to Dixon, No. 689,860, dated December 31, 1901.

With these and many other objects in view, which will more readily appear as the nature of the invention is better understood, the same consists in the novel construction, combination, and arrangement of parts which will be hereinafter more fully described, illustrated, and claimed.

In the accompanying drawings, Figure 1 is a plan view of one form of patterning-holder embodying the present invention. Fig. 2 is a transverse sectional view thereof. Fig. 3 is a plan view showing the applied position of the holder and illustrating a piece of lace-work in process of formation.

Like reference-numerals designate corresponding parts throughout the several figures of the drawings.

In carrying out the invention the holder is usually in the form of a plate of any desired shape, although in the preferable form it has the configuration of a disk or circular body. This disk or circular body (designated in the drawings by the numeral 1) may be made of any material suitable for the purpose—such, for instance, as celluloid, metal, wood, ivory,

papier-mâché, or equivalent material possessing special rigidity and lightness.

The holder-plate or disk-body 1 is provided therein with a plurality of concentric series of pin-receiving holes 2, one of which series is preferably arranged near the center of the plate or disk to admit of a different variety of designs for the center, such as lace buttons or medallions fastened in the center by pins 60 and working from the buttons or other medallions to the outside row of pins. In this connection it will be observed that the central group or series of pin-receiving holes 2 bear an important relation to those rows arranged 65 closer to the peripheral edge of the body. Also in the carrying out of the present invention the holder body, plate, or disk 1 is preferably provided in the peripheral edge thereof with a continuous series of edge notches 3, 70 which facilitate the positioning of pins at the edges in any desired location, according to the character of the work to be accomplished. Said notches 3 are also employed in the same manner as the pin-receiving holes 2, thereby 75 making a larger-size lace wheel or disk. Furthermore, these notches are used in combination with the receiving-holes in making an irregular edge to the lace.

All of the pin-receiving holes are designed 80 for the reception of common headed pins 4, adapted to be inserted in the holes and pressed into a suitable cushion or other equivalent body, which provides for retaining both the holder and the pins in place during the use 85 of the device for making lacework thereon. In the use of the device the pins are passed through the holes a sufficient distance to leave the heads projecting above the upper side of the plate or disk for working the 90 threads thereover in the making of the lace according to any pattern that may be selected.

A distinctive feature of the present invention resides in the formation of the holder 95 body, plate, or disk 1 with a convexed upper working surface 5 sloped regularly to the peripheral edge of the body and providing a rounding guide-surface for the needle as it is passed in and out among the threads in the 100 formation of the lacework. A convexed surface of the character indicated greatly facili-

tates the free and easy movement of the point of the needle, and hence permits of an easier and more rapid working than is possible on a perfectly flat surface, such as shown in the 5 patent aforesaid.

The manner of using the device herein described is not essentially different from that set forth in the patent, and the improvements reside particularly in the convexed working 10 surface, the central group of holes, and the peripheral series of edge notches.

From the foregoing it is thought that the construction, use, and many advantages of the herein-described patterning-holder will 15 be readily apparent without further description.

Having thus described the invention, what is claimed, and desired to be secured by Letters Patent, is—

1. A patterning-holder for making lacework 20 consisting of a plate convexed on its upper side and having a plurality of pin-receiving holes therethrough, the plate being notched at its peripheral edge.

2. A patterning-holder for making lacework 25 consisting of a plate convexed on its upper side, a plurality of concentrically-arranged series of pin-receiving holes, one of said series of holes arranged at or near the center of the body, and the plate provided with a 30 peripheral series of edge notches.

In testimony whereof I affix my signature in presence of two witnesses.

AUGUSTA PROCTOR.
